UNITED STATES PATENT OFFICE.

JOHN A. WHERRY, OF NEW ORLEANS, LOUISIANA, ASSIGNOR TO UNDERWOOD TYPEWRITER COMPANY, OF NEW YORK, N. Y., A CORPORATION OF DELAWARE.

TYPE-WRITER.

1,307,648.

Specification of Letters Patent. Patented June 24, 1919.

Application filed October 20, 1917. Serial No. 197,546.

To all whom it may concern:

Be it known that I, JOHN A. WHERRY, a citizen of the United States, residing in New Orleans, in the parish of Orleans and State 5 of Louisiana, have invented certain new and useful Improvements in Type-Writers, of which the following is a specification.

This invention relates to an improvement in typewriting machines, and more particularly to a sheet-collating device for assembling a number of sheets of different size or sheets of different character in different relative positions with respect to one another, and is illustrated in connection with features disclosed in my applications Nos. 15 155,380, filed March 17, 1917, and 184,820, filed August 7, 1917.

In the prior application No. 184,820, means was shown for reciprocating a pair of 20 bands wrapped around the platen for the purpose of collating work-sheets. This case differs from that application in providing a work-sheet holder which, in the form disclosed, comprises a fold which is secured to 25 the bands, so as to travel around the platen. This fold is provided with flexible side and bottom flaps, capable of being bent over on the body of the fold, so as to maintain the work-sheets on the fold and thus on the 30 bands which travel around the platen. The fold is further provided with impaling studs, which are preferably sharp enough to permit the impaling of the work-sheets without having been previously perforated.

35 The flexible side margins or flaps are provided with perforations registering with the impaling studs.

The platen is provided with a sectional 40 guide, so as to deflect the fold and the sheets carried thereby around the platen. This forms a convenient means of assembling the work-sheets at the front of the platen and inserting them on the platen by reversing the platen.

45 The improvement is shown as applied also to a modified form of collating device in which the fold is located at the entrance or rear side of the platen for assembling the work-sheets. This is an improvement on my 50 application No. 180,530, filed July 14, 1917.

Other features and advantages will hereinafter appear.

In the accompanying drawings,

55 Figure 1 is a perspective view, showing the collating device as in a position ready

to receive a plurality of work-sheets to be assembled for positioning on the platen.

Fig. 2 is a side view in elevation, showing the parts in a position similar to that of Fig. 1.

60 Fig. 3 is a view similar to Fig. 2, except that the collating device has been drawn around the platen to bring a line of the work-sheet, upon which it is desired to print, to the printing point.

65 Fig. 4 is a detail vertical section, showing the connection of the fold to one of the bands, and also the means of attaching the collating studs to the fold.

70 Fig. 5 is a view similar to Fig. 2, showing a modified form in which the fold is applied to the structure shown in my said application No. 180,530.

75 Referring more particularly to the separate parts of the device as embodied in the forms shown in the drawings, the platen 1 is secured to an axle 2 mounted to rotate on a carriage 3. The platen 1 is rotated in the usual way by line-space mechanism indicated in general at 4 and by hand-knobs (not shown). To travel back and forth with the rotation of the platen 1, there is provided a collating device, indicated in general at 5, on which work-sheets of various character may be assembled so as to bring predetermined lines in register with each other, whereby different parts on several work-sheets can be written on simultaneously.

80 The collating device 5 includes a pair of spaced bands 6 and 7, which are detachably secured to bars 8 and 9 counterbalanced by spring-actuated toggles 10 and 11. The bars 8 and 9 are guided for their movement by plates 12 and 13, so that the bands 6 and 7 will be held taut around the platen 1 by 85 the spring-actuated toggles 10 and 11. This is similar to the structure shown in my application No. 184,820.

90 The bands 6 and 7 are connected to move positively with the platen 1 by means of a sprocket arrangement which includes perforations 14 provided on the bands 6 and 7 and engaging sprocket teeth 15 provided on the ends of the platen 1. The bands 6 and 7 form a support for a work-sheet holder here- 95 in disclosed as a fold 16, which is secured to the bands 6 and 7 by rivets 16^a, Fig. 4. The fold 16 forms a means of assembling a number of work-sheets of different character, so that they can travel with the bands around 100 105 110

the platen 1. The fold 16 includes a back 17, side flaps 18 and 19 and a bottom flap 20. The flaps 18, 19 and 20 are capable of being folded over onto the back 17, so as to prevent 5 longitudinal and transverse movements of the work-sheets assembled in the fold.

For the purpose of securing the work-sheets in juxtaposition relative to each other and relative to the fold, the fold 16 is provided with a series of impaling studs 21 located at various intervals, and preferably provided with sharp points so that the work-sheets can be impaled thereon without being previously provided with perforations. The side flaps 18 and 19 are provided with perforations 22 registering with the impaling studs 21, so as to allow the studs to pass through the side flaps.

The bottom flap 20 may be provided with a notch 23. This flap 20 has a considerable stretch 24, whereby it may be properly gripped and guided in passing around the platen. The upper part of the flap 20 is bent at a crease line to form a leaf 25 extending over the side flaps 18 and 19, so as to catch them and insure their being folded flat on the back 17 when the fold as a whole passes around the platen 1. This is possible, as the lower flap 20 overlaps the side flaps 18 and 19 to a sufficient extent, so as to automatically deflect the lower ends of the side flaps 18 and 19 toward the back 17 of the fold.

The fold 16 and the work-sheets carried thereby are gripped to the platen 1 by the usual pressure feed rolls 26 and 27. These pressure feed rolls are the standard feeding and guiding device used on the Underwood typewriter, and are fully described in my above-mentioned application No. 184,820. They are mounted on rods 28 carried by arms 29 pivoted to a shaft 30. The arms 29 have secured thereto arms 31 which engage flat bottomed notches 32 provided in a rock 45 shaft 33. The rock shaft 33 spreads the arms 31 so as to remove the rolls 26 and 27 from engagement with the platen 1 against the tension of springs, not shown.

The shaft 33 may be rocked from a pressure feed roll release 34, which is connected thereto, by means of a link 35 and an arm 36 on the rock shaft 33. The rock shaft 33 may also be operated to release the pressure feed rolls 26 and 27 from a hand-lever 37, 55 which is connected to the rock shaft 33 by means of a link 38, a shifter 39, a link 40 and an arm 41 carried by the rock shaft 33. Incidentally, the shifter 39 disengages a detent 42 which engages the line-space wheel. 60 The release of this detent permits the rapid rotation of the platen by the hand-knobs for positioning the collating device.

The collating device is arranged to automatically bring the pressure feed rolls and 65 the detent 42 into action after they have been

released, when the collating device has been returned onto the platen a sufficient distance to bring the initial line of the work-sheets to the printing point. This includes a pin 43 adjustably mounted on one of the bands 6 70 in any one of a plurality of openings 44. The particular opening determines the stopping point of the collating device and the platen as a whole. The pin 43 is stopped in its movement by an arm 45 and a bell-crank 46. This bell-crank, in addition to determining the limit of movement of the pin 43 and thus of the collating device, also operates the hand-lever 37, so as to rock the shaft 33 and thereby permit the pressure feed roll spring to return the pressure feed rolls to their gripping position with relation to the platen 1.

A shield guide 47, Fig. 3, is warped around the under side of the platen 1, so as to 85 guide the fold 16 around the platen 1. This guide 47 forms a continuation of the plate 12, so that the flap 20 will pass properly around the platen 1. The guide 47 is sectional, so as to extend between the sections 90 of the feed rolls 26 and 27, and thus insure the flaps 18, 19 and 20 being smoothed out in passing around the platen 1.

In Fig. 5 the fold 16 is shown as applied to the collating device of the form shown 95 in my application No. 180,530. In this form the sheets are assembled at the rear of the platen instead of at the front and are assembled leading edge downward. This requires the assembling of the work-sheets in the manner in which they would ordinarily be inserted on the platen, and they will be brought to the printing point after assembling by a forward rotation of the platen. In this form the bands are similar to the 100 other form, except that but one spring-actuated lazy tong is used and the bands are drawn around the platen by a loop 48 formed therein. The fold 16 is similarly secured to the bands so as to pass around the platen. 105

It will thus be seen that a plurality of work-sheets of different character can be assembled in a pack with differently located lines in register with each other, so as to have the same subject-matter copied on different lines on the several sheets. The sheets will be held in their relatively assembled position both by the collating studs and the flaps 18, 19 and 20. The flap 20 insures the collapsing of the flaps 18 and 19 on the 115 back 17 of the fold, and thus insures the work-sheets being held in their position on the studs 21.

Variations may be resorted to within the scope of the invention, and portions of the 125 improvements may be used without others.

Having thus described my invention, I claim:

1. The combination with a platen, of a flexible supporting means passing around 130

said platen, and a fold secured to said flexible supporting means so as to travel therewith around said platen, and including a back with flaps secured thereto to overlap the 5 margins of the work-sheets placed upon the back, so as to maintain them in position in traveling around the platen.

2. The combination with a platen, of flexible supporting means wrapped around said 10 platen, and a fold secured to said flexible supporting means so as to travel therewith around the platen, said fold including a back with side flaps and an end flap secured to said back, said end flap overlapping said 15 side flaps, so as to automatically flatten said side flaps on said back on passing around said platen.

3. The combination with a platen, of a flexible support passing around said platen, 20 and a fold secured to said support including a back, side flaps integral with said back and arranged to fall in toward each other to a position parallel with said back, and a bottom flap on the edge of said fold nearest said 25 platen overlapping said side flaps to an extent to enable the deflection of said side flaps toward said back on said fold passing around said platen.

4. The combination with a platen, of a 30 flexible support connected to said platen to travel around the same, a fold secured to said flexible support, said fold including a back and side flaps capable of being bent to a position parallel with said back so as to

35 include between the back and the flaps work-sheets assembled in the fold, and impaling studs located on said fold for securing work-sheets on said fold.

5. The combination with a platen, of a 40 flexible support extending around said platen, a fold secured to said flexible support so as to travel with said support around said platen, said fold including a back, side flaps having perforations therein capable of being 45 bent parallel to said back so as to include work-sheets between said back and said side flaps, and studs on the back of said fold extending through said perforations in said flaps when the latter are folded onto said 50 back.

6. The combination with a platen, of a pair of bands wrapped around the ends of said platen, and a fold secured to said bands at its ends and extending from band to band 55 so as to travel with said bands around said platen, said fold including a back and flaps moved to a position parallel with said back in passing around the platen with said bands.

60 7. The combination with a platen, of a flexible support passing around said platen, and a fold secured to said flexible support, said fold including a back and a flap integral with said back at the lower margin of said 65 fold, said flap normally extending parallel

to said back for a considerable distance from the lower margin of the fold and being provided with a bent-out portion having a crease line connection with the major portion of the flap, so as to extend parallel to 70 the back of the fold in passing around the platen and automatically opened out when said fold is withdrawn from the platen.

8. The combination with a platen, of a flexible support passing around said platen, 75 and a fold secured to said flexible support, so as to travel around said platen, said fold comprising a back, side flaps integral with said back, and extending to a point short of the bottom margin of the fold, and a flap 80 integral with the lower margin of the back, and extending a considerable distance from the lower margin parallel with the back, said lower flap having a crease line, whereby the upper portion thereof will spring away 85 from said back, the upper portion of said flap overlying said side flaps, so as to automatically fold said side flaps with said back when said fold passes around said platen.

9. The combination with a platen, of a 90 pair of bands wrapped around said platen, and a collating device carried by said bands, said collating device comprising pointed collating studs on which work-sheets may be mounted, a flap to overlap the margins of 95 the work-sheets, and a second flap to overlap said first-mentioned flap to hold the latter in position while it is being fed around said platen.

10. The combination with a platen, of a 100 pair of bands wrapped around said platen, and a collating device on said bands, said collating device comprising collating pins adapted to pierce work-sheets which may be mounted on said collating device, and a flap 105 to overlap the margins of the work-sheets, said pins being effective to hold the work-sheets in position on said collating pins, and said flap being effective to hold the work-sheets on said pins while the collating device 110 is being fed around said platen.

11. The combination with a platen, of a flexible supporting means mounted so as to pass around said platen, and a flexible work-sheet holder secured to said supporting 115 means so as to travel therewith around said platen, said holder including a back having a side flap secured thereto to overlap the margins of work-sheets placed upon said back, so as to maintain them in position 120 while traveling around the platen.

12. The combination with a platen, of a flexible supporting means mounted for movement about said platen, and a flexible work-sheet holder secured to said supporting 125 means so as to travel therewith about said platen, said holder comprising a back having a side flap and an end flap secured thereto, said end flap being capable of overlapping said side flap, so as to flatten said side 130

flap against the work-sheets placed upon said back, as said holder is carried around said platen.

13. The combination with a platen, of a flexible support mounted for movement about said platen, a flexible work-sheet holder secured to said support so as to travel therewith about said platen, said holder comprising a back and a side flap capable of being bent to a position parallel with said back against the margins of work-sheets when placed in position in said holder, and impaling studs located on said holder for securing the work-sheets thereto.
14. The combination with a platen, of a flexible support mounted for movement

about said platen, a flexible work-sheet holder secured to said support, so as to travel therewith about said platen, said holder including a back, a side flap having 20 perforations therein and capable of being bent parallel to said back against the margins of work-sheets inserted between said back and said flap, and studs on the back of said holder so located as to extend through 25 said work-sheets and the perforations in said flap when the latter is folded against the margins of said work-sheets.

JOHN A. WHERRY.
